(57) **CLAIM**

The ornamental design for a monocular, as shown and described.

DESCRIPTION

1.1 is a perspective view of a monocular showing my new design;

1.2 is a front elevation thereof;

1.3 is a rear elevation view thereof;

1.4 is a top plan view thereof;

1.5 is a bottom plan view thereof;

1.6 is a right side elevation view thereof; and

1.7 is a left side elevation thereof.

The dark background in all figures is included for the purpose of providing contrast and forms no part of the claimed design.
